UNITED STATES PATENT OFFICE.

JOHN J. NASH, OF WATERBURY, CONNECTICUT, ASSIGNOR TO AMERICAN PIN COMPANY, OF WATERBURY, CONNECTICUT, A CORPORATION OF CONNECTICUT.

DESIGN FOR A BRACKET-CANOPY.

46,443.

Specification for Design.

Patented Sept. 22, 1914.

Application filed July 27, 1914. Serial No. 853,478. Term of patent 3½ years.

To all whom it may concern:

Be it known that I, JOHN J. NASH, a citizen of the United States, residing in Waterbury, in the county of New Haven and State of Connecticut, have invented a new, original, and ornamental Design for a Bracket-Canopy, of which the following is a specification when taken in connection with the accompanying drawing.

Figure 1 is a side elevation of a bracket

canopy embodying my design; and Fig. 2 is a top plan view of the same.

What I claim is:—

The ornamental design for a bracket canopy, substantially as shown.

JOHN J. NASH.

Witnesses:

H. J. STOOPS,
A. W. LASHER.
